CLAIM

The ornamental design for a golf club head, as shown and described.

DESCRIPTION

FIG. 1 is a front elevational view of a golf club head showing my new design.

FIG. 2 is a rear elevational view.

FIG. 3 is a left side elevational view.

FIG. 4 is a right side elevational view.

FIG. 5 is a plan view; and,

FIG. 6 is a bottom view.

The broken line showing is included for the purpose of illustrating and forms no part of the claimed design.
